IRVIN L. YOUNG, OF CHICAGO, ILLINOIS.

SHIPPING TAG.

Application filed March 8, 1927. Serial No. 173,775.

This invention relates to shipping tags, and more particularly to the reinforcing means therefor.

Simple as the common shipping tag may seem, it is significant that much study has been given the problem of producing a shipping tag which will suffer much handling and abuse without breaking away from the shipment or becoming torn or mutilated, and yet be inexpensively produced. The efforts of the past have resulted in the tag accepted as the present standard, such tag having its head portion reinforced by a circular patch on each side, and the combined plies perforated with the usual aperture. Small, or light duty tags are thus made, but the larger, or heavy duty variety include a metal eyelet in the aperture to further strengthen the tag against wear and pull by its twine or wire attaching loop.

While the tag as reinforced by standard methods is considered efficient and durable, it presents serious difficulties in the process of its manufacture which limit the output in quantity and quality. Thus, in the feeding of the metal eyelets, lack of uniformity in the dimensions and shape of the un clinched eyelet results in imperfect feeding of the latter. Further, in the clinching operation the necessary anvils receive undue wear, so that the clinching is incomplete and the tag aperture therefore poorly reinforced. The eyelet setting operation cannot be made sufficiently rapid for quantity production as the eyelet feeding and setting elements depart from accurate registration with the tag aperture.

In order to avoid the above difficulties, I have devised a novel tag reinforcement whose object is to enable the tag to be produced at a high rate of speed.

A further object my invention is to eliminate the need of exacting accuracy in the machinery applying the reinforcement.

The improvement also has for its object to eliminate the customary eyelet and round patches, and substitute therefor a simple combination having a wider reinforcing area.

Another object of the invention is to design the novel reinforcement with thinness and uniformity, in order that the tags may stack compactly and evenly.

A final but nevertheless important object of the invention is to design the novel reinforcement with a high protective value, permitting the stock of the tag itself to be of a lighter and cheaper grade.

With the above objects in view and others that may suggest themselves from the specification and claim to follow, a better understanding of the invention may be gained by reference to the accompanying drawing, in which—

Figure 1 is an elevation of the novel tag;

Fig. 2 is an edge view; and

Fig. 3 is a perspective view of the same in separated form, clearly showing its constituent parts.

Structurally considered, the novel tag is composed of the body card or sheet A, a reinforcing paper or fabric strip B under the top or head portion of the same, a guard strip C of tough fibre, metallic ribbon or preferably corrugated wire over the head portion, and finally a reinforcing paper or fabric strip D over the guard strip and head portion. The latter is then cut with biased corners E in the customary manner, and then punched with the usual aperture F at a medial point, the aperture bordering on the guard strip C on the body side of the tag.

The units from which the tag is constructed are sections cut transversely from a series of ribbon-like webs of the respective materials, such webs moving in unison between a lineal series of treating units, such as coating, pressing, punching and cutting devices. For the present form of tag, the movement of the material webs is necessarily in the direction of the imaginary lines G. Thus, picturing the parts A, B, C and D as an incidental portion of a composite web, moving from one side toward the other, it is not difficult to conceive

the application of suitable apparatus to first, coat the head portion of the card web A with a film of glue; next, lower the guard web C to lie upon and travel with the head portion;

next, gather either or both of the reinforcing webs B and D toward, and press them to, the head portion; next, run the latter between a punch unit to cut the aperture F; and finally run the assembly through a set of dies to define and cut the individual tags from the composite web. These operations may be carried out in the above or any other suitable order;

and the webs may have a continuous or intermittent motion.

While the properties of the tag, as concerning its use and durability, do not depend on any individual method of production—as long as the unitary and resulting assembly is in harmony with the showing in the drawing—the peculiar process described

and dealing with the treating of a composite, moving web is of vital importance when quantity production is considered, as will presently be apparent.

As anticipated, the novel tag receives the glued reinforcing ply B fully across the under side of its head portion; and the obverse side thereof likewise receives the reinforcing ply D after the special reinforcement or guard C has been laid. The pressing of the plies is sufficiently thorough to impress and embed the guard in the plies between which it is laid so as to become relatively immovable and virtually integral with the tag.

By the above construction, the head portion of the tag is reinforced in its entire width, so that such head portion will remain whole in case the body of the tag is torn or broken away from rough handling. The ample width of the said head portion makes it suitable to bear a registry number for the tracing of the shipment in case the body portion of the tag is missing. Also, by reinforcing the tag along its entire width, it is given sufficient strength or body and toughness to warrant the use of a lighter and cheaper stock for the body card or sheet A.

It should be noted that, although no special reinforcement seems to be provided about the tag aperture F, the three plies usually found are nevertheless present; and in addition, the special guard or barrier C is almost in immediate touch with the aperture on the side where the pull or tug of the looped twine or wire would be when some influence bears on the tag to detach it from the shipment. The guard, by its toughness and tenacity, presents an unyielding resistance to such influence. It is, therefore, safe to assume that the tag, or at least its head portion, will cling to its twine or wire attaching loop under any condition to which shipments are customarily subjected.

The guard C may be of simple, straight-line design or with a figure detail, as indicated. It is my preference, however, to have it in the form of a corrugated wire, since (1) it is easily made and therefore inexpensive; (2) it can be fed positively by a suitable machine in case it must be laid accurately; (3) it covers a greater area and therefore exerts a stronger hold upon the plies between which it is laid; (4) it becomes immovably impressed or locked in such plies; and (5) it cannot turn and loosen in places where the

plies have separated, due to imperfect sealing or pressing.

In doing away with the customary eyelet and substituting the elongated and tenacious guard C, the tag-making machine is relieved of the intricate setting and clinching units and their imperfections, as outlined in a foregoing section. Also, in eliminating the circular patches to reinforce the tag at the site of the aperture, other machine units of an involved character are rendered unnecessary. The simple assembly of the novel tag requires but an ordinary degree of precision for the proper grouping of the component parts and the cutting of the aperture and the individual tag outline. Hence, a properly designed machine may be operated at high speed, to produce tags in great quantities and on short order.

In handling the novel tag, it will be found thinner than the standard tag in the region of the head portion, due to the compactly compressed state thereof. Hence, when the tags are stacked in containers in customary quantities, the containers can be of much less than the usual height and therefore more cheaply produced. In stacking the novel tags, their thin head portions enable the stack to settle closer and hold more nearly to level formation. Also, the tags rest squarely when stacked and do not wobble, as their reinforced portions are of uniform thickness and not thicker in the middle as in the case of the patched or eyeleted standard tags.

It will thus be seen that my novel tag is an improvement in the art from the various points of view outlined. I have illustrated and described its preferred construction, but it is capable of miscellaneous minor changes and refinements in its further development, without however departing from the principle of my invention; and I consider such changes and refinements as coming within the scope and spirit of the appended claim.

I claim:

A shipping-tag comprising a body sheet, a reinforcing ply secured thereto at one end, a corrugated strengthening wire arranged transversely of said sheet and between said sheet and ply, said tag being provided with a cord receiving aperture adjacent said wire and inwardly thereof.

In testimony whereof I affix my signature.

IRVIN L. YOUNG.
